UNITED STATES PATENT OFFICE.

R. H. EMERSON, OF CHICAGO, ILLINOIS.

EARTH-CAR.

Specification of Letters Patent No. 10,775, dated April 11, 1854.

To all whom it may concern:

Be it known that I, RICHARD HENRY EMERSON, of Chicago, in the county of Cook and State of Illinois, have invented a new or Improved Railway-Carriage for the Transportation and Discharge of Earth, or other Loose Matters; and I do hereby declare that the same is fully described and represented in the following specification 10 and the accompanying drawings, letters, figures, and references thereof.

Of the said drawings, Figure 1, denotes a top view of my said gravel car or carriage. Fig. 2, is a side elevation of it. Fig. 3, is 15 a longitudinal and vertical section of it. Fig. 4, is an underside view of it.

The kind of car or railway carriage as improved by me is what is usually termed and known by the name of the "long car", 20 that is to say, one having its carriage supported on two truck frames, each of which is sustained by four wheels.

In the drawings, the platform of the carriage is shown at A, the two truck frames 25 at B and C. The wheels at E, E, E, &c., and the axles at F, F, F, &c. The platform of this car is made with an open space extending through it and between the turning bearings of the truck frame, from which 30 open space sides H, H, I, I, flare and extend upward so as to form with the doors applied to said open space a receptacle, I', for earth, gravel or other material. The bottom of the receptacle, I, is composed of two 35 series of doors or turning platforms K, K, K, L, L, L, each door, K, being about one half the width of each door, L, and the several doors or flaps being so arranged as that each door, K, shall be directly next to a 40 door, L, as seen in the drawings. Each one of the said doors is fastened upon one of a series of transverse shafts, a, a, which are situated with regard to the respective doors and turn in boxes or bearings b, b, b, 45 c, c, c, as seen in the drawings.

Extending longitudinally through the middle of the carriage and above the top of the receptacle, I', are two long shafts or axles, M, N. Each one has a crank, O, fixed 50 on its outer end and it also has a ratchet or cogged wheel, P, placed on it and made to work in connection with a retaining pawl, Q, connected to the end of the receptacle I', or made to turn vertically on a pin or 55 screw, c, projected from such end as seen in Fig. 1.

A bar or timber, R, extends over and parallel to the two axles before named and serves in connection with cross bars, T, T, T, to sustain four vertical crank shafts, S, S, S, S. Each of the crank shafts has a crank, U, on its upper end, while its lower end is formed with a projection or shoulder, d. The lower end of the shaft passes through a small slot, e, of the width of the crank shaft, and made through the large door, L, directly under said crank shaft. The object of this crank and its shoulder is to hold the door L, upward in a horizontal position, when the next adjacent door, K, is dropped down into an inclined position. Each two adjacent doors, K, L, has two chains, g, h, extended upward from them respectively and made of the same length and united at their upper ends to a chain, i, that winds around and is attached to one of the axles, M, N.

When the cranks of the several vertical crank shafts S, S, S, are turned so as to extend transversely across the car, the several doors L, L, L, do not rest on the shoulders of said crank shafts as they do when the cranks stand longitudinally of the car, and when such is the case the several doors may be caused to fall into inclined positions 80 by turning backward the two axles M, N. When, however the cranks stand in a longitudinal direction the larger doors L, L, will remain upward, while the lesser doors only will fall when the axle is turned backward. 85 This enables me to discharge at any one time but a portion of the earth or gravel contained in the car, or such as rested directly over the smaller doors, the larger doors upholding the larger or remaining 90 portions which are not to be discharged until after the car has been moved forward a short distance on the railway.

The peculiar slope which the earth with in the car takes after the smaller doors have 100 been opened and such earth as was directly above them has fallen out of the car, renders it necessary that, in order to drop half the load, over any doors, K, L, one door should be made much smaller or less in width than the other. By means of the smaller doors, we are enabled to drop at any one time smaller portions or less quantities of the earth, for these doors are much easier managed and can be raised or closed with much 105 less power than would be necessary to raise or operate the larger ones.

One of the truck frames has a leveler or scraper, V, affixed to it which is placed between two of the wheels and extends below their axle for the purpose of the leveling 5 down the dropped piles of earth when the car is moved forward. Each wheel if necessary may also have a guard scraper, W, placed in front of it and so applied as to be capable of being pressed down upon the 10 surface of the rail on which said wheel travels and remove or throw off any dirt which may fall thereon. Such removal taking place when the car is in motion, and being produced by the car dragging the 15 scraper against the earth. In the drawings, this scraper is shown as suspended from one end of a lever X.

I do not claim the invention of a car with hinged or turning flaps in the bottom, for 20 discharging earth or other materials; nor do I claim raising or lowering such doors or flaps by means of a windlass and chains or of securing them and working them by means of crank shafts and catches; nor do 25 I claim as new the attachment of a leveling

plate or scraper to a carriage for the purpose of spreading the earth dropped from the cars, as these devices have all been used before; but

What I do claim, as my improvement is— 30

The construction of a long car, arranged as described with two sets of doors, in the bottom of different breadths, which in combination with the chains, axles and crank shafts, and the attached leveling plate, V, 35 enables me to discharge and spread nearly one half of the load without discharging the whole; and to equalize the quantities of earth dropped by disengaging the different sets of doors, which could not be done, 40 if the doors were of equal width and only one half of them dropped at one time.

In testimony whereof, I have hereto set my signature this twenty sixth day of April, A. D. 1853.

RICHARD HENRY EMERSON.
